UNITED STATES PATENT OFFICE.

GEORGE ACKERMANN, OF CINCINNATI, OHIO, AND JOHN WAGNER, OF DAYTON, KENTUCKY, ASSIGNEES OF ONE-THIRD TO CHARLES F. LOUDON, OF CINCINNATI, OHIO.

MACHINE FOR FILLING CANS.

SPECIFICATION forming part of Letters Patent No. 297,549, dated April 29, 1884.

Application filed December 27, 1883. (No model.)

To all whom it may concern:

Be it known that we, GEORGE ACKERMANN, a resident of Cincinnati, in the county of Hamilton and State of Ohio, and JOHN WAGNER, 5 a resident of the town of Dayton, in the county of Campbell and State of Kentucky, have invented certain new and useful Improvements in Machines for Filling Cans, of which the following is a specification.

10 Our invention in general relates to a machine for filling cans with suitable material—such, for example, as fruit, vegetables, meats, or other food, or material of any kind sufficiently small or comminute to pass through the machine.

15 The principal objects of our invention are to provide mechanism which shall deliver to the cans the requisite amount of material to fill such can, and no more, and which also shall force the material into the can.

The several features of our invention, and the various advantages resulting from their use conjointly or otherwise, will be apparent from the following description.

20 Referring to the drawings forming part of this specification, Figure 1 is an elevation of one side of the machine; and Fig. 2 is an elevation of the opposite side of the machine—that portion of the machine lying above a horizontal plane through the dotted line $x\ x$ of Fig. 1. Fig. 3 is a sectional elevation, the section being taken at the vertical transverse center of the machine—viz., through the dotted line $y\ y$ of Fig. 1, and looking toward the 25 side which is at the left in Fig. 1. Fig. 4 is a view showing the interior of the filling-tube and the plungers for forcing the material into the cans. Fig. 5 is an enlarged sectional view of one of the plungers, showing the preferred 30 construction of same. Fig. 6 is a plan view of the table or shelf on which the cans to be filled are supported. Figs. 7 and 8 represent the preferred mechanism for cutting off the supply of material to the cans.

40 A represents the table or equivalent supporting frame-work of the machine, and on top of this table are secured the ends of a semi-circular tube, A' . On top of this tube A' are formed two short tubes, $a\ a'$, preferably of the

same diameter as said tube A' , and on top of 50 these last-named tubes is secured a plate, B, which plate is provided at each side with the upturned flanges or guides b . (See Fig. 8.) The plate B at the points to which the tubes $a\ a'$ are secured is provided with holes of a 55 diameter equal to that of the said tubes, so that fruit or vegetables, &c., will fall freely through the tubes $a\ a'$ and into the semicircular tube A' .

Above the plate B and between the guides 60 b is a plate, B' , (see more particularly Fig. 8,) capable of sliding longitudinally between said guides, and on top of this plate B' are secured short tubes $C\ C'$, the distance between these tubes $C\ C'$ being such that when the tube C is 65 directly over the tube a the tube C' will be beyond the tube a' and out of communication with the latter, as shown in Fig. 1.

Above the plate B' is another plate, D, to the lower side of which are secured the short 70 tubes $d\ d'$, which latter tubes respectively telescope into the tubes $C\ C'$. The plate D at the points to which the tubes $d\ d'$ are secured is perforated to allow material to fall freely 75 into said tubes. The horizontal plane of this plate D is adjustable by means of standards 70 D' , the lower ends of which rest upon and are secured to the plate B' , and the upper ends of which pass through the plate D. The ends of 80 these standards above and below said plate are 80 provided with set-nuts $d^2\ d^3$. The plates $B'\ D$, tubes $C\ C'\ d\ d'$, and standards D' thus form a 85 sliding carriage, which, for convenience of reference, we will designate as an entirety by the letter D^2 , and which is caused to slide back and forth by suitable mechanism, preferably by such as is hereinafter described. Above this carriage D^2 is a trough or box, E, in which the fruit or vegetables, &c., to be canned are placed. This box E is supported at each end by a yoke 90 or bracket, E', the lower ends of which are secured to lugs e , connected to the plate B, the lower ends of the yokes E' being provided with slots e' , through which pass set-screws e^2 , which are screwed into the lugs e , to secure the yokes 95 to said lugs. This construction is the preferred one for enabling box E and its appendages to be vertically adjusted.

of tube a' , is subsequently in turn forced out of the end A^3 of the tube A' , and also through a funnel M' , when the latter is present, into another can.

- 5 At each side of the machine, below each end of the semicircular tube A' , is a shelf or table, M , (see Fig. 1,) on which the cans to be filled are placed, and on top of this shelf M are the adjustable guides or stops m , (see Fig. 6,) 10 against which the can is placed to keep it directly under the end of the funnel or mouth of tube A' , and these stops may be adjusted to keep the center of different-sized cans directly under the center of the end of the said 15 funnel or mouth of tube A' .

In conjunction with each end of the tube A' is secured a funnel, M' , whose interior is in communication with the tube A' . The lower end of each of these funnels is adapted to fit 20 into the upper open portion or top of the can and in the top of the shelf M , and on a level therewith, and directly under the open end of the funnel M' is a circular disk, N , upon which disk the can rests when under the funnel M' . 25 The distance between the lower end of the funnel M' and the shelf M is a little greater than the height of the cans to be filled, so that the can may be readily placed beneath the funnel. The disk N is capable of being raised, 30 thus raising the can, so that the mouth of the funnel M' will enter the top of the can. In Fig. 1 the can W is shown in dotted lines, at the right hand in said figure, resting down on the shelf, and at the left-hand side is shown 35 raised to cause the funnel to enter the top of the can.

One of the simplest and most convenient means for raising the disk N is that shown in the drawings. The disk N is secured to the upper end of a rod, N' , which is capable of sliding up and down in supports n , and the lower end of this rod N' rests on one end of a lever, N^2 , pivoted to the edge of the frame A , the other end of which is connected to a treadle, 40 N^3 , by a rod, n' , so that when the treadle is depressed the disk N and the can shown in dotted lines are elevated, as shown at the left-hand side of Fig. 1. The weight of the filled can will usually cause the disk to descend and 45 the treadle to be raised as soon as the pressure of the operator's foot is removed from the treadle; but to positively insure in such a case the descent of the disk and the treadle, we prefer to employ, in conjunction, a spring— 50 in this instance a spiral one—connected at one end to an adjacent leg, R , of the frame, or equivalent fixed support, and at the other end connected to the inner end of lever N^2 .

The piston-heads $K' K^2$ cannot enter the funnels M' , and a certain amount of the material being canned would remain in these funnels were no means provided for removing it, and when the can is removed from under said funnels this material would fall onto the shelf 55 M ; and to prevent this we construct the piston-heads, preferably as shown in section in Fig. 5. The head is made in the form of a

hollow shell, k , through the upper side or end of which the piston-rod K passes, and to the other end of the piston-rod, within the 70 shell k , is secured the upper end of a supplemental piston-head, K^3 , the diameter of which is equal to the diameter of the opening in the lower end of the funnel M' . To the upper end of this supplemental piston is secured a disk, 75 k' , between which and the lower—that is, the front—end of the shell k is a spring, k^2 , preferably a spiral one, as shown, the tendency of which is to constantly keep the disk k' at the upper end of the shell k , and the lower end of 80 the supplemental piston K^3 is thus kept on the same plane as the lower end of the shell k , except when the spring k^2 is compressed. Thus when the piston-head is away from the end of the semicircular tube A' the front end of the 85 piston, including the front end of the supplemental piston, is in a continuous plane, and the material in this tube is forced in front of the piston into the funnel M' . When the piston-head reaches the upper end of the funnel, 90 the lower end of the shell k strikes the upper end of the funnel, as shown in Fig. 5, and can go no farther; but the piston-rod K continuing to advance, the spring k^2 is compressed, and the supplemental piston K^3 is advanced into 95 the funnel, and the material in the latter is thus forced out into the can.

The various parts of the operating mechanism of the machine as above described are so arranged that when the piston K has completed its stroke to the end of the semicircular tube the piston K^3 is just above the opening of the tube a into the semicircular tube, as shown in Fig. 4. The can under the right-hand end of the semicircular tube has now been filled, 100 and is removed by the operator at that side of the machine, and the operator at the other end of the tube places a can on the shelf M under that end of the tube. At this stage in the operation of the machine the cam J has moved 105 the carriage D^2 to the end of its movement toward the right in Fig. 1, and the tube $C d$, which has previously been filled with material through the tube F , is directly over the tube a . The contents of the tube $C d$ thus fall through 110 the tube a into the semicircular tube A' in front of the piston-head K^2 . The continued revolution of the shaft G causes the piston-rod K to move toward the opposite end of the semicircular tube A' , and the piston-head K^2 115 forces the material in front of it into the can under that end of the tube A' , in the manner above described. While this movement of the piston is being made, the cam J moves the carriage D^2 toward the left in Fig. 1, and the 120 tube $C' d'$, which has been filled with material through the tube F' , is brought directly over the tube a' , and the material falls from the tube $C' d'$ through the tube a' and into the semicircular tube in front of the piston K' , 125 and the tube $C d$, which is now away from the upper opening of the tube a and under the tube F , is again filled. The continued revolution of shaft G now causes the piston-rod K' 130

to move toward the end A^3 of tube A' , and this piston-head K forces the material in front of it into an empty can placed under this end of the tube A' . In this manner the carriage 5 D^2 and the piston-rod K are alternately moved to the right and to the left, and the cans under the right and left hand ends of the semicircular tube are alternately filled, the box E being kept supplied with the material to be canned. 10 Of course, liquid as well as or along with solid material may be delivered through tube A' into the can.

Our device also enables us, when it becomes desirable, after the can has been partly filled 15 with a definite liquid or liquor, before being brought under the tube A' , the can then being placed under said tube, to fill the remaining space of the can with a different desired material, usually of a non-liquid character, through 20 the tube A' .

It may be desirable at times to prevent the delivery of material to the semicircular tube A' through one or both of the tubes a or a' without stopping the motion of the machine, and 25 to accomplish this we provide a suitable device. A desirable device for this purpose consists of sliding gates O , (see Figs. 7 and 8,) one such gate being provided for tube a and another for tube a' . Each gate is held in position by guideways P , secured to the under side of the plate B , and is capable of being slid over the upper opening of its respective tube a or a' . These slides are each provided 30 with an appropriate handle, as p , by which the slide may be moved back and forth, so that the operator at either end of the tube A' may 35 at will stop the delivery of material to the cans.

From the above description it will be seen 40 that we are enabled to fill cans very rapidly and without any waste or danger of overflowing the cans, as just a sufficient quantity, and no more, of the material to be canned is delivered to each can.

Obviously one half portion of the tube A' and one of the pistons K' or K^2 , as the case may be, are (when desired) to be dispensed with, along with the apparatus particularly adapted to enable it to carry out its own particular 45 functions, as distinguished from the other portion of the tube and from the piston of the latter, and from the mechanism for carrying its functions of feed, delivery, &c., into effect.

While the various features of our invention 50 are preferably employed together, one or more of such features may be employed without the remainder. When desired, one or more of such features may, so far as applicable, be employed in connection with filling mechanism other than that particularly herein specified.

What we claim as new, and desire to secure 55 by Letters Patent, is—

1. In a machine for filling cans, the combination 60 of a curved tube occupying a portion of the circumference of a circle, a piston reciprocating in said tube, and mechanism for

regulating the supply of canning material to the piston and delivering said material in front of the piston, substantially as and for 75 the purposes specified.

2. In a machine for filling cans, a tube having a supply-opening and a delivering-opening, an interiorly-reciprocating piston, plate B , a measure-tube sliding with plate D , and a supply-box having a delivery tube or opening for delivery, at stated periods, to the measuring-tube, of the material to be canned, substantially as and for the purposes specified.

3. In a machine for filling cans, a tube carrying a reciprocating piston, plate B , adjustable telescopic measure, sliding plate D , and a supply-box having a tube or opening for delivery to the measure, substantially as and for the purposes specified.

4. A machine for filling cans, consisting of a semicircular tube, having an interior piston provided with mechanism for causing it to move in both directions in said tube, and mechanism, substantially as described, for delivering the material to said tube alternately in front of the opposite ends of said piston, the latter being adapted to force the material from the ends of said tube, substantially as and for the purposes specified.

5. In a can-filling machine, the semicircular tube A' , provided with an interior piston, said piston being connected to mechanism for causing it to move back and forth in said tube, and the tube A' being provided with the inlet-tubes a a' , in combination with the box or receptacle E , and intervening mechanism, substantially as described, for causing some of the contents of said box to be alternately delivered to the tubes a a' , substantially as and for 105 the purposes specified.

6. The semicircular tube A' , provided with inlet-tubes a a' , and the box E , supported above said tube and provided with tubes F F' , in combination with the sliding carriage D^2 , carrying the tubes C d and C' d' , said last-named tubes being adapted to communicate alternately with the tubes F F' above and the tubes a a' below, substantially as and for the purposes specified.

7. The semicircular tube A' , provided with inlet-tubes a a' , having a plate, B , secured on their upper ends, and the box E , provided with tubes F F' , and supported on brackets E' , connected to the plate B , in combination with the sliding carriage D^2 , consisting of the plates D and B' , and carrying the tubes C d and C' d' , the plate B' resting and sliding on the plate B , and the plate D resting against the lower ends of the tubes F F' , substantially 120 as and for the purposes specified.

8. In a can-filling machine, the combination of the telescopic tubes C C' d d' , sliding plate D , rigidly connected to tubes d d' , plate B , and a forcing-tube provided with tubes or openings a a' , and the supply-box E , having tubes or openings F F' , substantially as and for the purposes specified.

9. The combination of the box E , provided

with tubes F F', and supported on brackets E', connected to plate B, and capable of vertical adjustment, and the carriage D², resting and capable of sliding on said plate B, and consisting of the plate B' D, carrying the telescopic tubes C d and C' d', the plate D, when the plate B' rests on the plate B, being held against the lower ends of the tubes F F' by means of the standards D', having set-nuts d² d³, substantially as and for the purposes specified.

10. The semicircular tube A', provided with the interior piston-heads, K' K², connected to opposite ends of a piston-rod, K, the latter being connected to one end of a vibrating rod, L, the other end of said rod being connected to a rock-shaft, L', in combination with the sliding carriage D², constructed substantially as described, and provided with a yoke, I', and the cam J, connected to a shaft, I, and engaging with said yoke, and the operating-shaft G, and connecting and operating mechanism, substantially as described, for causing the cam J to revolve and the rod L to vibrate, substantially as and for the purposes specified.

25. 11. The semicircular tube A', having an interior piston, K K' K², connected to one end of a rod, L, the other end of said rod being connected to a rock-shaft, L', provided with a crank-arm, L², in combination with the driving-shaft G, shaft G², gear-wheels G' g², crank G³, and connecting-rod l, substantially as and for the purposes specified.

12. The sliding carriage D², constructed and supported substantially as described, in combination with the shaft I, having cam J, and the driving-shaft G and shaft G², and connecting and operating mechanism, substantially as described, for causing the shaft I and cam J to revolve to cause the carriage D² to move back and forth, substantially as and for the purposes specified.

13. In combination with the curved tube suitably supported, a funnel, M', located at the end of the tube, and a piston-head operating in said tube, the head consisting of a shell, k, and an interior supplemental piston, K³, adapted to be advanced beyond the end of the shell k, substantially as and for the purposes specified.

14. The semicircular tube A', connected to the table A, and having at each end a funnel, M', in combination with the interior piston-heads, K' K², each head consisting of a shell, k, and an interior supplemental piston, K³, adapted to be advanced beyond the end of the shell k, substantially as and for the purposes specified.

15. The combination of the curved tube and funnel M', and a hollow piston-head, K, operating in said tube, and the supplemental piston K³, adapted to lie in the hollow piston and to be advanced beyond the end of the latter, and an elastic spring for retracting the supplemental piston when pressure thereon by the piston-rod is removed, substantially as and for the purposes specified.

16. The combination of the shell k and the interior supplemental piston, K³, connected to the piston-rod K, and having at its inner end a flange or stop, k', and the spring k², compressed between said flange or stop and the bottom of the shell k, substantially as and for the purposes specified.

17. The semicircular tube A', constructed and supported substantially as described, and the shelves M, located beneath the ends of said tube, and each provided with a disk, N, and mechanism, substantially as described, for causing said disks to be raised and lowered, substantially as and for the purposes specified.

18. The table or shelf M, provided with adjustable stops m and with the disk N, in combination with the treadle N³, rod n', lever N², and rod N', for causing said disk to be raised, substantially as and for the purposes specified.

19. The semicircular tube A', having inlet-tubes a a', the upper end of the last-named tubes being each provided with a sliding gate or cover, O, substantially as and for the purposes specified.
